United States Patent Office

Des. 184,166
Patented Dec. 30, 1958

184,166

COIN OPERATED SHAVER CABINET

John L. Carmichael, San Diego, Calif.

Application February 1, 1957, Serial No. 44,696

Term of patent 7 years

(Cl. D52—3)

Fig. 1

Fig. 2

Fig. 3

Fig. 1 is a perspective view of a coin operated shaver cabinet showing my new design;

Fig. 2 is a side view thereof; and

Fig. 3 is a top plan view thereof taken on an enlarged scale.

The electric razor and sterilization lamp shown in broken lines are depicted for illustrating purposes only.

I claim:

The ornamental design for a coin operated shaver cabinet, as shown and described.
